UNITED STATES PATENT OFFICE.

SAMUEL E. ALLERTON, OF CHICAGO, ILLINOIS.

MACHINE FOR SCORING CAN BODIES.

Application filed December 20, 1922. Serial No. 607,950.

To all whom it may concern:

Be it known that I, SAMUEL E. ALLERTON, a citizen of the United States, residing at Chicago, in the county of Cook and State of Illinois, have invented certain new and useful Improvements in Machines for Scoring Can Bodies, of which the following is a specification.

This invention relates to improvements in machines for scoring can bodies.

In prior machines used for scoring or forming grooves in can bodies, the several cutters have usually been mounted on the same rotatable shaft. Where the cutters wear away unevenly, this resulted in varying the depth of the grooves and making it difficult to tear off the strip of metal when the finished can was later opened. Furthermore, difficulty was encountered, due to the springing of the shaft. As the depth of the grooves is only a few thousandths of an inch, it has been very difficult heretofore to obtain grooves of uniform depth.

My invention aims to overcome these difficulties by providing means for mounting the cutters on a rigid support, which will not spring appreciably, and arranging the cutters one behind the other on different supports, so that each forms a groove independently of the others.

One of the objects of the invention is to accomplish this result by mounting the cutter so that it may rotate on a non-rotatable support, thereby permitting the support to be fastened very rigidly.

Another object is to provide a hard bushing between the cutter and its support, to reduce wear. Other objects and advantages will be apparent from the description herein-after given of the preferred embodiment of the invention.

In the drawings—

Figure 1 is a top plan view of the machine which embodies the invention;

Fig. 2 is a section on the line 2—2 of Fig. 1;

Fig. 3 is a plan view of the blank or can body;

Fig. 4 is an elevation of one of the driving collars; and

Fig. 5 is an elevation of one of the cutters or scoring knives.

Power is transmitted to the pulley 1 mounted on a shaft 2, the latter carrying a gear 3, which drives other gears 4, 5 and 6 through a series of idler gears 7, 8 and 9.

As shown in the sectional view of Fig. 2, the gear 6 is mounted on a shaft 10 which rotates in a bushing or bearing 11 and has a collar 12 to prevent endwise movement. The shaft has a reduced extension 13 passing through a bearing 14 with a gear 15 on the end thereof, which meshes with a gear 16 above it, thereby driving a shaft 17 parallel to and mounted above the shaft 13. The bearing is forced upwardly by means of springs 18 and may be adjusted by means of the studs 19 to maintain proper alignment. At the end of the shaft 17 is a collar 20 which drives the cutter 21. Said cutter rotates on a hard bushing 22 which latter is mounted on a rigid supporting shaft 23 also adjustable by means of suitable springs and studs 18 and 19. The collar 20 is provided with a plurality of projecting pins 20', which engage in a plurality of radial slots 21' in the cutter. The bushing 22 is held onto the end of the shaft 23 by a plate 22'.

The blank passing through the machine slides along the guideway 24 which extends from one end of the machine to the other and passes under the successive cutters 21, 25, 26 and 27, each of which is mounted and driven in a manner similar to the first one described. Said cutters do not rotate in the same plane, however, but in parallel planes each one being set over a little further from the end of the guideway 24 so as to score the blank 28 (Fig. 3) in parallel lines spaced apart a short distance. The blank before leaving the machine passes between two rollers 29, which draw the blank from under the cutters and also flatten it. These rollers are driven by a train of gears 30, 31 and 32. The guideway 24 may be curved and the axes of the cutters arranged radially, in grooving a body for a tapering can.

The support for the bushing 22, being non-rotatable, may be very rigidly mounted so it will not yield appreciably, as the cutter 21, for example, rotates above the lower roller 33 with the blank between them. Furthermore, such wear as does take place is confined entirely to the lower side of the bushing, whereas it is uniformly distributed over the cutter and the bushing may therefore be rotated to prolong its use. Furthermore, its support 23 may be very accurately adjusted so as to provide for a groove of the exact thousandths of an inch desired.

By the arrangement I provide, of cutters mounted in series one behind the other, the

depth of each groove may be accurately adjusted and no one cutter is dependent for its accuracy upon the others, as has been the case heretofore when several cutters have 5 been mounted on the same shaft. In the machines used heretofore, a large percentage of the can bodies scored have been defective, whereas with my improved machine the defective products have been almost eliminated.

Although the cutters in the machine shown in the drawings are positively driven, they may be mounted as idlers and turned by the blank passing between them and the 15 positively driven rollers beneath.

What I claim is:—

1. In a machine of the class described, a rotatable shaft, a stationary support in axial alignment therewith, a cutter rotatably mounted on said support, and means for driving said cutter from said shaft.

2. In a machine of the class described, a stationary support, a cutter thereon, means for maintaining said cutter in uniform 25 groove cutting relation and means for rotating said cutter.

3. In a machine of the class described, a stationary support, a bushing thereon, a rotatable cutter mounted on said bushing, said 30 bushing being adapted for adjustment for maintaining said cutter in position to cut grooves of uniform depth and means for rotating said cutter.

4. In a machine of the class described, a 35 rotatable shaft, a stationary support in axial alignment therewith, a cutter rotatably mounted on said support, and means for driving said cutter from said shaft, said driving means being carried on the end of 40 said shaft adjacent said cutter.

5. In a machine of the class described, a rotatable shaft, a stationary support in axial alignment therewith, a cutter rotatably mounted on said support, and means for

driving said cutter from said shaft, said 45 driving means being carried on the end of said shaft adjacent said cutter and having a portion engageable therewith.

6. In combination, two parallel rotatable shafts, means for driving one from the other, 50 a fixed support mounted at the end of one of said shafts, a cutter rotatably mounted thereon and driven from said adjacent shaft, and a roller mounted on the other shaft in the plane of said cutter.

7. In a machine of the class described, comprising a bed plate, a series of stationary supporting members mounted thereon, a bushing on the end of each of said members, a cutter rotatably mounted on each of said 55 bushings, said cutters being mounted to rotate in separate and distinct planes parallel to each other, a rotatable shaft passing beneath each of said supporting members and extending beyond the same, a rotatable shaft 60 above each of said last named shafts parallel thereto and terminating adjacent said cutters, gears for driving one of said shafts from the other in each pair, and means turning with said last mentioned shafts for 70 rotating said cutters.

8. In a machine of the class described, a rotatable shaft, a stationary support in axial alignment therewith, a cutter rotatably carried by said support, driving means for said 75 cutter carried by said shaft, and means for compensating for the wear of said cutter.

9. In a machine of the class described, a rotatable shaft, a stationary support in axial alignment therewith, a bushing on said support, a cutter rotatably carried by said bushing, and driving means on said shaft for rotating said cutter, said bushing being adjustable on said support to compensate for 80 the wear of said cutter.

In testimony whereof, I have subscribed my name.

SAMUEL E. ALLERTON.
